Filed Feb. 20, 1968, Ser. No. 10,648

Term of patent 14 years

Int. Cl. D19—08

U.S. Cl. D25—1

FIG. 1 is a front perspective view of an arithmetic teaching device embodying my new design, and showing a selectively positionable counting piece exploded therefrom;

FIG. 2 is a top plan view of the teaching device;

FIG. 3 is an elevational view taken from the right side of FIG. 1; and

FIG. 4 is a fragmentary rear elevational view, the upper righthand corner being broken away for convenience of illustration.

We claim:

The ornamental design for the arithmetic teaching device, as shown and described.
